UNITED STATES PATENT OFFICE.

WESLEY CLARK, OF LOVELAND, COLORADO.

ROAD-GRADER.

1,183,954.

Specification of Letters Patent. Patented May 23, 1916.

Application filed September 15, 1914. Serial No. 861,851.

To all whom it may concern:

Be it known that I, WESLEY CLARK, a citizen of the United States, residing at Loveland, in the county of Larimer and State of Colorado, have invented certain new and useful Improvements in Road-Graders, of which the following is a specification.

My invention relates to new and useful improvements in road graders and has for its primary object the provision of a device of this character which may be adjusted for various types of work.

A further object is the provision of means for holding the various sections in their adjusted positions.

With these and other objects in view the invention consists in the novel details of construction and arrangement of parts which will be more clearly understood from the following description and drawings, in which,

Figure 1 is a plan view. Fig. 2 is a longitudinal sectional view on the line 2—2 of Fig. 1. Fig. 3 is a longitudinal sectional view with the center point raised, and Fig. 4 is a transverse sectional view on the line 4—4 of Fig. 1.

In the drawings, I have shown the grader consisting of two sections indicated generally by the letters A and B, but it will be understood that any desired number of sections may be used without departing from the spirit of the invention and adapting the device for use on roads of different widths.

The section A comprises a front plate 1 having the scraper plate 2 secured to the bottom edge thereof, and the rear plate 3, the two plates being connected by means of the angle iron strips 4 and 5. The section

B comprises the front plate 6 having the scraper plate 7 secured to the bottom thereof and the rear plate 8 connected to the front plate by means of the angle iron strips 9 and 10.

The sections are connected by means of the hinge 11, said hinge being pivotally connected at the bottom of each section by the pins 12 and adjustably connected toward the top of the sections by means of the removable pins 13 which enter the perforations 14 formed in the plates 1 and 6 of the sections. A bar 15 is secured to the angle iron bar 9 of the section B and at the outer end is provided with a plurality of perforations 16. The end of this bar is curved as is clearly shown in Fig. 1 of the draw-

ings and passes through a slot formed in the angle iron connecting bar 5 of the section A. A removable pin 17 is adapted to enter the perforations in the bar 15 and engages the angle iron connecting bar 5. As is more clearly shown in Fig. 1 the ends of the rear plates 3 and 8, respectively, of the sections A and B are bent at right angles to form the abutting ends 18. Eye bolts 19 and 20 are provided on the sections A and B, respectively, for attaching the traction power of any character.

Having fully described the detailed construction of my device it is thought that the operation will be clear. It will be noted that I have provided a grader which is adapted for both horizontal and vertical adjustment whereby it may be used as a drag for merely leveling the road or for surfacing the road in such a manner that it will be higher in the center than at the sides. When it is desired to horizontally adjust the sections the pin 17 may be removed from the perforations 16 in which it may be found and placed in any of the other perforations for adjusting the sections to the desired degree. When it is desired to elevate the center of the grader for forming the road higher in the center than at the sides the pins 13 are removed and adjusted in any of the perforations 14 to secure the desired elevation.

Having fully described my invention what I claim as new and desire to secure by Letters Patent is:—

1. A road grader comprising two scraping sections, a hinge between said sections to permit horizontal angular adjustment between the latter, a fixed horizontal pivotal connection between the bottom of the hinge and each section, and an adjustable connection between the top of the hinge and said sections to permit vertical angular adjustment between the same.

2. A road grader comprising two scraping sections, a hinge between the said sections to permit horizontal angular adjustment between the latter, means for maintaining said sections at different angles of adjustment, a fixed horizontal pivotal connection between the bottom of the hinge and each section, and a removable hinge connection between the top of the hinge and each of said sections to permit vertical angular adjustment of the same.

3. A road grader comprising two scraping

sections, a hinge connecting said sections to permit horizontal angular adjustment between the latter, a sector plate on one of said sections movable through a slot in a portion of the frame of the other section, a pin adapted to be inserted in one of a plurality of perforations in said sector to hold said scraping sections in adjusted angular position, a fixed horizontal pivotal connection between the bottom of the hinge and each of said sections, and removable pins adapted

to be inserted in holes in the upper end of said hinge, and one of a plurality of holes in each of said sections to permit vertical angular adjustment of the sections. 15

In testimony whereof I affix my signature in presence of two witnesses.

WESLEY ^{his} X CLARK.
